UNITED STATES PATENT OFFICE

BEN ALTHEIMER, OF UNIVERSITY CITY, MISSOURI, ASSIGNOR TO MYRTLE ALTHEIMER,
OF UNIVERSITY CITY, MISSOURI

METHOD OF MAKING RADIATOR SHIELDS

Application filed March 28, 1931. Serial No. 525,890.

My invention relates to a method of making radiator shields, and more particularly to the method of making paper radiator shields.

5 The invention has among its objects, the production of a radiator shield of the kind described, which may be made of a minimum width of paper sheet, and which will be simple, speedy, neat, economical, and efficient and 10 satisfactory for use wherever found applicable.

A further object of my invention is to so fold a paper radiator shield that the same can be readily stacked for storage and shipment, and occupy a minimum of space when 15 so packed.

Many other objects and advantages of the method and construction herein shown and described, will be obvious to those skilled in 20 the art to which this invention appertains from the disclosures herein given.

To this end, my invention consists of the novel construction, arrangement and combination of parts, and the method employed in 25 obtaining the same, as shown and described, and more particularly pointed out in the claims.

In the drawings, wherein like reference characters indicate like or corresponding 30 parts throughout the views,

Figure 1 is a rear elevation of a radiator with my improved radiator shields in place thereon;

Figure 2 is a cross-sectional view, taken 35 substantially along the line 2-2 of Fig. 1;

Figure 3 is a side elevation of one form of shield;

Figure 4 is a similar view of my preferred 40 form;

Figure 5 is a similar view of another modification;

Figure 6 is a similar view of a further modified form;

45 Figure 7 is a plan view of the rectangular blank for making the preferred form, indicating the lines of fold;

Figure 8 illustrates the form of shield shown in Fig. 3 as the same appears fully 50 folded;

Figure 9 shows the shield shown in Fig. 8, and partially folded or unfolded;

Figure 10 shows the blank shown in Fig. 7 and with the first line of fold made thereon;

Figure 11 shows the second step of folding 55 of the same;

Figure 12 shows the third step of folding;

Figure 13 shows the fourth step of folding 60 of the top portion of the shield;

Figure 14 shows the fifth step of folding 65 of the same;

Figure 15 shows the next step and with the projecting tab ready for the securing to the body portion of the shield; and

Figure 16 shows the preferred form as it 70 appears when the top portion is fully folded and secured in place.

In carrying out the method of forming the preferred embodiment of my invention, as shown in Figs. 1, 4, 7, and 10-16 inclusive, 75 I provide a sheet of relatively thin material such as sized cloth or paper of rectangular shape or outline, it being understood that this paper should not be too flimsy, and preferably be substantially impervious to the passage of dust therethrough. A good type or paper for this purpose is the well-known type of paper called "kraft" paper, this paper being relatively tough and able to withstand quite a bit of handling, both during the 80 course of manufacture and while in service.

This sheet of paper A is preferably marked or scored as indicated in Figure 7, in any suitable manner, or the relative distances for folding may be made in any other desirable 85 manner so as to facilitate the actual folding operations upon the sheet.

The longitudinal or side edges of the sheet A are indicated at 1-1 and are truly parallel with one another, while the top and bottom 90 edges 2-2 are parallel and perpendicular to the edges 1-1, so as to form a true rectangular sheet.

Adjacent the top edge of the sheet are indicated three lines of fold, namely 3, 4, and 5, at 95 progressively increasing distances from the free edge 2 (top) and parallel therewith and with one another. At a distance quite a bit greater than the spacing between the first-mentioned three lines, is another line 6, the 100

distance between the line 6 and the adjacent line 5 indicating the depth of the top of the radiator shield. That is, the distance between the lines 5 and 6 will be increased if the radiators upon which the shields are to be placed are deeper (from front to back), and will be correspondingly decreased in case the radiators R are not as deep as that shown upon the blank. Of course, it is to be understood that in all events, it is better that the top of the shield projects beyond the corresponding front edge of the radiator, so that the dust arising therethrough and agitated outwardly can be caught in the dust flange or trap provided in the shield.

The distance from the line 6 to the bottom of the sheet indicates the height of the shield and may be anything less than the actual height of the radiator itself, the intermediate line of fold 7, being simply for folding the shield into a compact package.

The manner of folding the top portion of the shield will now be described, especial reference being had to those figures of the drawings which particularly illustrate the preferred modification. The first step in the method is to fold the top edge of the blank sheet upon itself along the topmost line of fold 3, as shown in Fig. 10. Then both edges of the sheet are folded at the top corners, only one corner being shown in the drawings, the corners being folded inwardly and diagonally and preferably at an angle of 45 degrees as shown, along the line 8, as shown in Fig. 11, in which position the top edge of the previously folded portion is brought down to the line of fold 5, third from the top edge of the sheet.

Next, the longitudinal edges of the sheet are folded inwardly toward one another, and down onto the previously folded portions, so as to provide the longitudinally extending strips 9, these strips being folded along the lengthwise lines of fold 10 until the free edge 11 of the sheet coincides with and forms an extension of the longitudinally extending edge of the triangular portion 11 previously formed. By folding in this manner, the large triangular portion 11 will be substantially bisected as shown in Fig. 12.

The next step in the operation of making the shields is to fold the sheet downwardly on the third innermost line of fold 5, bringing the top of the previously folded sheet to the position shown in Fig. 13.

The next step is folding the portion last folded, and shown in Fig. 13, so as to bring the longitudinally extending edge 12 back onto the sheet until said longitudinal edge 12 is positioned transversely to its previous position and is brought into registry with the then top edge of the folded sheet (on the line of fold 5), as shown in Fig. 14.

A further step consists in temporarily withdrawing the longitudinally folded strip

9 from beneath the folded portions at the top of the sheet, so as to cause a triangular portion or tab of four-ply thickness and indicated at 13 to be withdrawn and extend beyond the top of the sheet when the strip 9 is again brought to its folded position, as shown in Fig. 15. In order to facilitate the temporary withdrawal of the longitudinal strip 9 the previously folded portions are held together by clamping or other pressure, in any suitable manner, and then the strip 9 flipped back from beneath the previously folded portions and again permitted to assume its folded position, as shown in Fig. 15.

Fig. 16 shows the triangular tab portion 13 pasted or otherwise suitably secured in place so as to retain the corners of the shield in their folded position.

It may again be mentioned that the detailed folding operations hereinabove described, relate only to the forming of the portion of the shield that covers the top of the radiator, and that the depending portions of the shield may be formed or folded in some suitable manner so as to make a neat and compact article for sale and shipment, somewhat as is shown in Figs. 8 and 9.

To attain this end, the bottom edge of the sheet may be brought up toward the top, as on the line of fold 7, and then the sides of the sheet are folded toward one another, as shown in Fig. 9 so that one folded substantially triangular portion overlaps the other portion. Then these overlapped portions are folded upwardly and preferably so that the point 14 may be inserted beneath the previously folded top portion of the shield.

The other modifications shown in the drawings illustrate other designs of folding so that the corners will have slightly different appearances, but in all cases it is to be noted that the shield will have a back wall portion extending downwardly from behind the radiator, the side edges of the same extending forwardly into the room, and having a top member extending forwardly over the top of the radiator, and with a downwardly extending flange entirely about the sides and front of the top portion, and in addition there is a dust-catching flange 15 provided by the first described step of folding.

Having thus described my invention, it is obvious that various immaterial modifications may be made in the same without departing from the spirit of my invention; hence I do not wish to be understood as limiting myself to the exact form, arrangement, construction, and combination of parts, or the manner of making the same, except as limited by the art to which this invention appertains, and the claims as hereto appended.

What I claim as new and desire to secure by Letters Patent is:

1. The method of forming a radiator

shield, comprising taking a single rectangular sheet of dust-impervious paper and folding the same adjacent one end upon itself; folding diagonally at the corners of said end to form a triangular portion; folding said sheet lengthwise inwardly at the sides; folding the sheet parallel to first-mentioned fold; folding diagonally from said corners to the top of the sheet; withdrawing the longitudinally folded strip to thereby withdraw a triangular portion of quadruple ply at the top of the sheet; and then folding said last-mentioned portion against said lengthwise strip.

2. The method of forming the top portion of a radiator shield, comprising taking a single sheet of dust-impervious fabric rectangular in outline and having three parallel lines of fold marked adjacent the top of the sheet blank; folding said sheet on the topmost line; then folding diagonally at the corners from said line to the lowermost line to form a triangular portion; folding from sides to form strips terminating at the longitudinally extending edge of said triangle; folding 25 along said third line; folding the corners upwardly to the top edge of the sheet; withdrawing each side strip to expose a triangular piece at the top; and then folding said last mentioned triangular portion against said sheet.

3. The method of making a radiator shield, comprising taking a single rectangular sheet of dust-impervious paper and folding the same adjacent one end upon itself; folding diagonally at the corners of said end to form a triangular portion; folding said sheet lengthwise inwardly at the sides to substantially bisect said triangle; folding the sheet parallel to said first-mentioned fold to the lowermost edge of said triangle; folding diagonally upwardly from said corners to the top of said sheet; temporarily withdrawing the lengthwise folded strip from thereunder to thereby withdraw a triangular portion of 45 quadruple ply at the top of the sheet; and then folding said last-mentioned portion against said lengthwise strip.

4. The method of making a radiator shield, comprising taking a single rectangular sheet of dust-impervious paper and folding the same adjacent one end upon itself; folding diagonally at the corners of said end to form a triangular portion; folding said sheet lengthwise inwardly at the sides to substantially bisect said triangle; folding the sheet parallel to said first-mentioned fold to the lowermost end of said triangle; folding diagonally upwardly from said corners to bring downwardly extending previously folded 55 edge to the top of said sheet; holding folded portion together inwardly beyond the lengthwise fold and temporarily withdrawing the lengthwise folded strip from thereunder to thereby withdraw a triangular portion of 65 quadruple ply at the top of the sheet; and

then folding said last-mentioned portion against said lengthwise strip.

5. The method of forming the top portion of a radiator shield, comprising taking a single sheet of dust-impervious paper rectangular in outline and having three parallel lines of fold marked adjacent the top of the sheet blank; folding on upper-most line; folding diagonally at corners from said line; folding from sides to form side strips terminating at 75 longitudinally extended edges of triangle to third line to form a triangular portion; folding along said third line to conceal said triangle; folding the corners upwardly so that the longitudinal edge will be flush with the 80 top edge of the sheet; temporarily withdrawing the side strip to expose a triangular piece at the top; and then folding said last mentioned triangular portion against said sheet.

In testimony whereof I have affixed my 85 signature.

BEN ALTHEIMER.
